(57) CLAIM

We claim the ornamental design for a disposable absorbent article, as shown and described.

DESCRIPTION

FIG. 1 is a top plan view of a disposable absorbent article, showing our nw design;

FIG. 2 is a front elevational view thereof;

FIG. 3 is a rear elevational view thereof;

FIG. 4 is a bottom plan view thereof; and,

FIG. 5 is a side elevational view thereof.

The broken line showing on the surface of the claim is for illustrative purposes only and forms no part of the claimed design.
